(57) **CLAIM**

The ornamental design for toy llama, as shown and described.

DESCRIPTION

The patent or application file contains at least one drawing executed in color. Copies of this patent or patent application publication with color drawing(s) will be provided by the Office upon request and payment of the necessary fee.

1. Toy llama

1.1 : Front

1.2 : Right

1.3 : Left

1.4 : Perspective

1.5 : Top

1.6 : Back

1.7 : Bottom

The characteristics of the designs for which protection is sought include the patterns, shapes, configuration and ornamentation of a toy llama; the color shown is not part of the design for which protection is sought.
